TYPOGRAPHICAL MACHINE

Herman R. Freund, Brooklyn, N. Y., assignor to
 Intertype Corporation, Brooklyn, N. Y., a corporation of New York

Application February 26, 1937, Serial No. 128,008

12 Claims. (Cl. 199—45)

The present invention relates to improvements in typographical machines and more especially to those of the class shown and described generally in U. S. Letters Patent No. 436,532, granted Sept. 16, 1890, wherein character-bearing matrices are stored in channeled magazines in the machine and, when released, fall through assembling means to an assembling point to form a composed matrix line for presentation to a slug casting mold, the matrices being subsequently carried to a distributing mechanism which returns them to their proper storage channels in the magazine from which they were drawn.

The invention relates more particularly to machines of this general class which are constructed to carry a plurality of matrix magazines each containing matrices of a different font, the magazines being inclined and arranged in superposed relation to form a column or stack which may be shifted to present one or another magazine in operative relation to the usual assembling and distributing mechanisms in the machine. It relates, moreover, to such plural magazine machines whether provided with single assembling and distributing means for cooperation with only one magazine at a time, as the so-called "non-mixer" machines for straight matter composition, or with assembling and distributing means such, for example as assembler guideways and two distributors for simultaneous cooperation with two magazines, as in machines of the so-called "mixer" type for composition requiring mixed type faces in the same line.

In machines of the so-called "non-mixer" type, the devices which shift and control the location of the magazine column are so constructed that each adjacent magazine is presented successively to the single assembling and distributing means. For machines of the so-called "mixer" type containing four matrix magazines in the column, two distinct forms of construction have been proposed, one form being constructed with a capacity for presentation of only the upper pair and the lower pair of magazines to the double assembling and distributing devices and the other with a capacity for the presentation of each adjacent pair of magazines to such assembling and distributing devices.

The primary object of the present invention is to combine in a single machine, whether of the "non-mixer" or the "mixer" type, the dual capacity whereby the column of magazines may be shifted, at the will of the operator, to present either each adjacent magazine or pair of magazines or non-adjacent magazines or pairs there-

of to the assembling and distributing devices. For example, the present invention aims to enable, in a "non-mixer" machine containing at least three magazines, the selection for use of either adjacent or non-adjacent magazines, as desired, and in "mixer" machines containing at least four magazines, the selection for use of either adjacent or non-adjacent pairs of magazines as may be desired. This dual capacity for the selection of magazines results not only in a more flexible machine but also aids the operator, it being evident that if shifts can be made directly to the particular matrix fonts required, whether they be located in adjacent or non-adjacent magazines in the column, time can be saved and moreover confusion of the operator or inadvertent selection of a wrong magazine is minimized.

To attain these results, the present invention provides controlling means, settable at the will of the operator and which, according to its setting and during the shifting of the column of magazines, permits the magazine column to assume operative positions corresponding to adjacent magazines or adjacent pairs thereof or causes the column to shift directly from one operating position to a non-adjacent one without assuming an intermediate position or moving into operative relation with the parts of the machine with which it would normally become associated in such intermediate position. More specifically and as shown in the present instance, a cam member is provided on which the lower end of the magazine column rests and by which the lower end of the magazine column is guided during its shifting movements, said cam member normally providing as many successive magazine locating positions as there are magazines or magazine pairs in the column, and a controlling selector or switch is associated with said cam member which, when appropriately set by the operator, will render inoperative at will intermediate positioning of the magazines, thus guiding the magazine column during the shifting operation directly into only such non-adjacent operating positions as may be desired.

In the accompanying drawings:—

Figure 1 is a side elevation of the upper portion of a typographical machine of the class hereinbefore referred to, the present invention being shown applied to a shiftable column of four magazines, the uppermost pair of magazines being shown in operative position.

Figure 2 is a side elevation, partly in section and on an enlarged scale, showing the controlling

selector in operative position and the column of magazines in cooperation therewith during the magazine shifting operation.

Figure 3 is a view similar to Fig. 2 but shows the selector in inoperative position and the column of magazines located to present the middle pair thereof in operative position.

Figure 4 is a partial section taken on the line 4-4 in Fig. 2, looking forwardly or in the direction of the arrows.

Similar parts are designated by the same reference characters in the several figures.

In the drawings, 1, 2, and 3 represent stationary parts of the main frame of a typographical machine of a usual and well known form, and 4 represents so-called side brackets rigidly secured to the main frame member 1, one of these brackets being provided at each side of the machine. The parts just described constitute the frame of the machine which supports the shiftable column of magazines, and 5 and 6 represent usual forms of assembler front and distributor mechanism respectively, the arrangement being such that by shifting the magazine column on the supporting brackets 4, a magazine or a pair of magazines at a time may be brought into operative relation with the assembler front and distributing mechanism.

The invention, for purposes of illustration only, is shown in the present instance applied to a machine of the "mixer" type provided with four magazines 7 and double assembling and distributing mechanisms. The magazines 7 are each carried, in an inclined position, on a frame 8, these frames being secured together in spaced relation by upper and lower tie-plates 9 and 10 respectively, the superposed magazines constituting the magazine column, together with their supporting frames and connecting tie-plates constituting a magazine unit which is shiftable forwardly and rearwardly in the main frame of the machine. The magazine unit is supported in the machine by a pair of rollers 11 journaled on stub shafts 12 at each side of the magazine unit, the stub shafts being secured to and projecting laterally from the outer sides of the lowermost frame 8 and about midway in the length thereof, the rollers 11 riding on tracks 13 formed on the upper edges of the respective brackets 4 and thereby supporting the magazine column, and the lower end of the magazine column rests freely on a cross shaft 14 on each end of which is secured a pinion 15, one on each side of the magazine unit, these pinions engaging toothed racks 16 on the respective brackets 4. The magazine column may be shifted along the tracks 13 and toothed racks 16 by a chain gearing enclosed in housings 17 and 18, the housing being mounted near its forward end on a pivot 19 so that it may swing freely in a vertical plane with respect to the machine frame 3, and the housing 17 is pivotally connected to the housing 18 by a shaft 20 which permits the adjacent ends of the housings 17 and 18 to swing freely relatively to one another in a vertical plane, the upper end of the housing 18 being pivotally mounted on the shaft 14 so that it may swing about said shaft as an axis. In using such means for shifting the magazine column, turning of a handle 21 connected to a sprocket wheel 21^a around which the chain gearing passes causes rotation of the shaft 14. The shaft 14 is connected at each end to the respective stub shafts 12 by links 22, one at each side of the magazine unit. Rotation of the shaft 14 will cause the pinions 15 thereon to travel for-

wardly or rearwardly along the respective racks 16 and, through the agency of the connecting links 22 between the shaft 14 and the shafts 12, the magazine column will be moved forwardly or rearwardly on the supporting brackets 4 until the usual lugs 23 on the magazine frames 8 come to rest on locating blocks 24 secured to the inner sides of the brackets 4, said lugs and locating blocks serving to sustain the magazine column in position to accurately present the desired magazine or pair of magazines in proper cooperative relation with the assembling and distributor devices.

The construction thus far described is similar to that disclosed in U. S. Letters Patent No. 1,650,552 granted November 22, 1927 and is well known in commercial machines of this class. In the present instance however, the shaft 14 serves merely to impart forward and rearward movement to the magazine column resting freely on it since it does not lift the forward end of the magazine column, as in said patent. It will be understood however that in using magazines of the kind herein shown, which have their matrix releasing escapements 25 set back somewhat from their lower forward ends, it is necessary to lift the lower forward end of the magazine column sufficiently high during the shifting operation to allow the lower ends of the magazines to clear the usual escapement actuating reeds 26 in the main frame. For this purpose, there is provided in the present instance a pair of cam blocks 27, one secured on the inner side of each of the brackets 4, and cooperating rollers 28 are provided on the lower tie-plates 10 at each side of the magazine unit, the rollers 28 being positioned above and adapted to ride on the respective cam blocks 27.

With this construction, when the column of magazines is shifted forwardly or rearwardly, the rollers 28 on the magazine unit, unless otherwise directed, will follow the contour of the cam blocks 27, and these cams are each provided with a pair of lobes 27^a which provide a depression 27^b between them and also depressions 27^c and 27^d at their forward and rear ends respectively. Each of these cam blocks thus provides, in the present instance, a series of three depressions to receive the respective roller 28, the different positions of this roller with respect to the cam block being designated A, B, and C respectively. When the uppermost pair of magazines are in operative relation with the double assembler front 5 as shown in Fig. 1, at which time the upper ends of this pair of magazines will be in operative relation with the distributor mechanism 6, the rollers 28 will occupy the rear position A on the cam blocks 27. When the middle pair of magazines is in operative relation with the assembler front 5 and distributor 6, the rollers 28 will occupy the middle position B on the cam blocks 27, as shown by the full lines in Fig. 3, and when the lowermost pair of magazines in the column are in operative relation with the assembler front and distributor mechanism, the rollers 28 will occupy the forward position C as indicated by the dotted lines in Fig. 3.

Preferably, the rollers 28 do not rest in contact with the cam blocks 27 while in any of the positions A, B or C but lie slightly out of contact therewith in order that the selected magazine or magazines will be firmly and accurately seated in operative position by the usual positive engagement of the lugs 23 on the magazine unit with the locating blocks 24 on the main frame. 75

It may also be pointed out that in the particular construction shown, the magazines 7 which rest on the respective frames 8, are slidable rearwardly thereon, and the lower magazine of the pair selected for use is slid rearwardly on its frame to some extent before each column shifting operation and then slid forwardly at the completion of such operation. Thus, in Fig. 3, the lower magazine of the middle pair is shown 10 by the dotted lines in the rearward position and will be slid forwardly on its frame as a final step in completing the shifting operation, to bring this magazine into working relation with its channel of the assembler front. Since this 15 sliding movement of the magazines on their frames, however, is merely occasioned by the particular form of matrix escapements and actuating reeds shown and has no material importance so far as the present invention is concerned it 20 is deemed unnecessary to explain the details of any specific construction that may be suitable for the purpose.

It will be understood that the cam blocks 27 provide as many successive magazine locating 25 positions A, B and C as there are adjacent pairs of magazines in the column. According to the present invention, a controlling selector or switch 29 is associated with each of the cam blocks 27, these selectors or switches being mounted to 30 swing vertically on pivot pins 30 which may be secured to and project inwardly from the respective brackets 4, whereby these selectors or switches may be thrown into and out of cooperation with seats 21 formed in the upper portions 35 of the lobes 27^a of the respective cam blocks 27.

As shown in Figure 3, the selector or switch 29 on the right hand bracket 4 is shown in inactive position and when both selectors or switches occupy such position, the rollers 28 on 40 the magazine unit are free to follow the entire contour of the respective cam blocks 27 and occupy any of the three magazine locating positions A, B or C. In Figure 2 however, the selector or switch 29 is shown in active position, it 45 resting on the seats 31 on the respective cam blocks 27, and when the selectors or switches occupy such position, they serve in effect to bridge the depressions 27^b in the respective cams, that is, the portion of the cam contour which the rollers 28 would ordinarily follow in assuming the middle magazine locating position B. It will be seen from Figs. 3 and 4 that the portions of the lobes 27^a of the cam blocks above the seats 31 are reduced in width to accommodate the 50 selectors or switches 29, thus allowing the latter, when in active position as shown in Figs. 2 and 4, to lie in the paths of the respective rollers 28. Also, the portions 32 and 33 of the selectors or switches 29, which portions lie adjacent respectively to the 55 foremost and rearmost slopes of the cam lobes 27^a conform to the contour of these portions of the cam blocks.

In operation, when the selectors or switches 29 are set in active position as shown in Figs. 1 and 60 2, the rollers 28 on the forward portion of the magazine unit will follow the cam blocks 27 only along the foremost and rearmost slopes thereof, these rollers travelling between these slopes along the selectors or switches 29. Thus, when the column of magazines is shifted from the rear position 65 A of the rollers 28, which corresponds to the operative position of the upper pair of magazines, the selectors or switches 29 will prevent the rollers 28 from assuming the middle position 70 B corresponding to the operative position of the

middle magazines or the adjacent magazines of the upper and lower pairs, the selectors or switches 29 thus serving to guide the magazine column directly from a position in which the upper pair of magazines are in operative position 5 to a position in which the lower pair of magazines are in operative position, the rollers 28 moving directly from the position A to the non-adjacent position C. Thus, by merely setting or adjusting the selectors or switches 29, the operator of a "mixer" machine may shift back and forth directly from one active pair of magazines to a non-adjacent pair, or he may shift between adjacent magazines, at will. Similarly, on a "non-mixer" machine, the selectors or switches 10 29, applied as herein described, afford the facility of selecting either adjacent or non-adjacent magazines for use and of shifting directly between the selected magazines in either instance. 15

While the invention is shown in the present instance applied to a so-called "mixer" machine in which the magazines are brought in pairs into operative relation with the assembler and distributor means, the invention is also applicable, as hereinbefore stated, to so-called "non-mixer" 20 machines in which the magazines are brought singly into operative relation with the assembling and distributor means, in which case the assembler front and distributor mechanism would be single instead of double for cooperation with 25 each magazine singly as it is brought into operative position.

I claim as my invention:

1. A typographical machine comprising a frame supporting matrix assembling means, a 35 magazine unit containing a column of matrix magazines, said unit being shiftable relatively to said frame, means for guiding the magazines to bring one or another thereof, in a predetermined order, into operative relation with said assembling 40 means, and means operable at will and cooperable with said guiding means to bring certain of the magazines in a different order, into operative relation with said assembling means.

2. A typographical machine comprising a 45 frame supporting matrix assembling means, a magazine unit containing a plurality of superposed matrix magazines and shiftable to bring one or another of the magazines into position for use, means for guiding the magazines to bring 50 them, in predetermined order during shifting of said unit, into operative relation with said matrix assembling means, and means controllable at will and cooperable with said guiding means to prevent the bringing of certain of the magazines 55 into such operative relation.

3. A typographical machine comprising a frame supporting matrix assembling means, a magazine unit containing a plurality of superposed matrix magazines and shiftable relatively to said frame, means for guiding the magazines, during the shifting of said unit, to bring them in successive order into operative relation with said assembling means, and means controllable at will and cooperable with said guiding means to prevent certain of said magazines from assuming operative 65 relation with the assembling means.

4. A typographical machine comprising a frame supporting matrix assembling means for cooperation with a pair of matrix magazines, a magazine unit containing a plurality of pairs of matrix magazines and shiftable relatively to said frame, means for guiding the magazines during the shifting of said unit to bring the pairs of the magazines and adjacent magazines of said pairs into 70 75

operative relation with said assembling means, and means controllable at will for preventing said adjacent magazines of the pairs from assuming said operative relation.

5. A typographical machine comprising a frame supporting matrix assembling means for cooperation with a pair of matrix magazines, a magazine unit containing a column of upper and lower pairs of matrix magazines and shiftable relatively to said frame, means for guiding the magazines during the shifting of said unit to allow one pair of said magazines, the adjacent magazines of said pairs and the other pair of magazines to successively assume operative relation with said assembling means, and means controllable at will and cooperable with said guiding means to prevent said adjacent magazines of said pairs from assuming said operative relation.

6. A typographical machine comprising a frame supporting matrix assembling means, a magazine unit containing a column of matrix magazines and shiftable relatively to said frame, means including a cam having portions for positioning the magazines successively in operative relation with said assembling means during the shifting of said unit, and a device cooperable with said cam to render a portion thereof inoperable.

7. A typographical machine comprising a frame supporting matrix assembling means, a magazine unit containing a column of matrix magazines and shiftable relatively to said frame, means including a cam having a series of portions for guiding the magazines to and from operative relation with said assembling means, and means controllable at will and operable to render one of said guiding portions of the cam inoperable.

8. A typographical machine comprising a frame supporting matrix assembling means, a magazine unit containing a column of matrix magazines and shiftable relatively to said frame, means including a cam having a series of depressions therein for raising and lowering the matrix discharge ends of the magazines to guide them to and from operative relation with said assembling means, and means settable at will into position to bridge one of said depressions.

9. A typographical machine comprising a frame supporting matrix assembling means, a magazine unit containing a column of matrix magazines and shiftable relatively to said frame, means including a cam having a series of depressions therein for guiding the matrix discharge ends of the magazines to and from operative relation with said assembling means, and a switch settable into cooperation with said cam to render an intermediate depression therein inoperable.

10. A typographical machine comprising a frame supporting matrix assembling means, a magazine unit containing a column of matrix magazines and shiftable relatively to said frame, a cam on said frame having a series of depressions therein and a part on said magazine unit cooperative with said cam for positioning the matrix discharge ends of the magazine in operative relation with said assembling means during the shifting of said unit, and a switch mounted adjacent to said cam and movable at will into bridging relation with a depression therein to guide said part on the magazine unit idly past said depression.

11. A typographical machine comprising a frame supporting matrix assembling means, a magazine unit containing a column of matrix magazines in inclined position, means mounted to ride on said frame for supporting the magazine unit for shifting movement relatively to the frame and also for pivotal movement about an axis approximately midway of the length of said unit, supporting members on the magazine unit below said axis, and cams mounted on the frame at opposite sides of the magazine unit and having portions on which said supporting members ride for guiding the lower ends of the magazines to and from operative relation with said assembling means.

12. A typographical machine comprising a frame supporting matrix assembling means, a magazine unit containing a column of matrix magazines in inclined position, means mounted to ride on said frame for supporting the magazine unit for shifting movements relatively to the frame and also for pivotal movement about an axis approximately midway of the length of said unit, a rotatable shaft mounted shiftably in the frame and having means thereon cooperative with the frame for effecting said shifting movements, links coaxially connected to said shaft and to said pivotal supporting means for the magazine unit, means mounted on the supporting frame and cooperative with said rotatable shaft for guiding the lower ends of the magazines to and from operative relation with the assembling means, a pair of pivotally jointed members, one pivoted coaxially of said rotatable shaft and the other extending to the front of the machine and pivoted on the frame, gearing supported by said members and connected to said rotatable shaft for operating it, and means located at the front of the machine for operating said gearing.
